UNITED STATES PATENT OFFICE.

FRANK C. BOWMAN, OF BROADWAY, VIRGINIA.

BROOM BRIDLE.

Application filed August 23, 1921. Serial No. 494,685.

To all whom it may concern:

Be it known that FRANK C. BOWMAN, a citizen of the United States of America, residing at Broadway, in the county of Rockingham and State of Virginia, has invented new and useful Improvements in Broom Bridles, of which the following is a specification.

The object of the invention is to provide a simple, efficient and readily applicable broom bridle or holder for engagement with the head of a broom as a means of reinforcing the strands thereof and shortening to the desired extent the flexible portions thereof of to suit the purposes for which the broom is designed, the bridle being of such construction as to adapt it for successive use on different broom heads; and with this object in view the invention consists in a construction and combination of parts of which a preferred embodiment is shown in the accompanying drawings, wherein:—

Figure 1 is a view of a bridle embodying the invention applied in the operative position to a broom head.

Figure 2 is a similar view of the bridle detached with the members thereof disconnected.

Figure 3 is a longitudinal sectional view of the bridle with the members interlocked.

The bridle is of sectional construction embodying separable members 10 and 11 each of which is of looped form and consists of a single blank of strap or sheet metal or equivalent material. These members are disposed in reverse relation with reference to the broom head indicated at 12 and which may be of any ordinary or conventional form, to the end that the edge portions of the head are respectively received in the loops of said members, and the inwardly extending arms of the members are provided with interlocking means whereby the overlapped portions thereof may be secured together to hold the broom head edgewise at any desired degree of compression.

In the construction illustrated one arm of each member is provided with a series of slots 13 while the other arm is provided with tongues 14 struck out of the material of the arm and disposed in approximate par-

allelism therewith, and furthermore one arm of each of the members, preferably the arm which carries the tongues 14 is provided with an ear 15 of triangular or pointed form secured to and extending inwardly from the arm and designed to engage with the strands of the broom head to establish an interlocking relation between the bridle and the head.

The arrangement of the members in reversed relation provides for the overlapping of the tongued arm of one member by the slotted arm of the other member as shown in Figure 2, and by extending the tongues through the slots and folding them into parallel relation with the arms as shown in Figure 3, after a suitable or preferred relative adjustment of the members has been attained to apply the required edgewise compression to the head, the bridle will be held in place with the flexibility of the fibres or strands of the head limited to a length suitable for the particular purpose for which the broom is designed.

It will be noted from the construction illustrated that the two elements constituting the bridle are precisely alike but when arranged with their looped ends opposite the tongues on the arm of one element are positioned for engagement with the slots in the arm of the other element and the tongue is being arranged in approximate parallelism with the arms, the two members may be moved longitudinally towards each other so that the tongues may be engaged in succeeding slots until the desired adjustment is secured, the tongue swinging inward as the members are moved towards each other. In transportation, the members can be arranged in a nesting relation in which case the tongues of the two members will be adjacent each other and the slots correspondingly adjacent each other, the deflection of the tongues from the surface of the arms being sufficient to provide an interlocking engagement when the two members are in such nesting relation.

Having described the invention, what is claimed as new and useful is:—

A broom head bridle consisting of separable substantially U-shaped members arranged in opposed relation with the arms of

each member in overlapping relation with those of the other, one arm of each member being provided with upstruck tongues disposed in slightly divergent relation with the surfaces of said arms and the remaining arms being formed with slots for engagement by said tongues, the arms carrying the tongues slidably engaging the inner faces

of the arms having the slots for the successive engagement of the tongues with the slots as the two members are moved longitudinally towards each other in the attachment of the same to a broom head.

In testimony whereof he affixes his signature.

FRANK C. BOWMAN.
